UNITED STATES PATENT OFFICE.

CHARLES JEAN-BAPTISTE VIGUERIE, OF PARIS, FRANCE.

GRAIN SEPARATOR.

Application filed March 28, 1925, Serial No. 19,104, and in France April 9, 1924.

The present invention has for its object to provide an improved grain separator particularly utilizable for separating commingled grains or seeds with a view to sorting 5 out one or several kinds of the said grains or seeds from the other commingled elements.

It has previously been proposed in apparatuses of this character to separate commingled grains or seeds by means of socketed 10 discs or Archimedean screw-blades made fast on a rotating shaft extending longitudinally through a drum-like casing in which the said grains or seeds are fed, said discs or 15 blades dipping into their mass so as to cause the proper grains or seeds to get into the said sockets and to be lifted and then dropped off and taken away by appropriate discharging devices, thus ensuring the required 20 separation.

According to the invention, a grain separator pertaining to the type referred to but having an improved structure and an increased efficiency is provided, said separator 25 being mainly characterized by the fact that its separating elements have a large number of sockets or alveoli on their outer working faces and are constituted by ring members of frusto-conical or dished shape 30 arranged in juxtaposed relation to one another externally or internally of a rotatable cylinder so as to form a zig-zag or saw-tooth shaped outline.

By this improved arrangement, the actual 35 working surface of the separating elements of the apparatus or, in other words, its separating capacity is considerably enhanced by comparison with the capacity of prior grain separators. Moreover the new arrangement of the juxtaposed ring-shaped 40 separating elements facilitates the getting of the proper grains into their alveoli whereby the output of the apparatus is still further increased.

Other features and advantages of the improved grain separator according to this invention, particularly so far as the structure of the separating elements and the discharging means for the separated and unseparated 45 grains are concerned, will incidentally appear in the following description and will be more specifically pointed out in the appended claims.

In the accompanying drawings:—

Fig. 1 is a side elevational view of a grain separator according to the invention where-

in the separating elements are arranged in juxtaposed relation externally of their supporting cylinder, the outer casing being partly broken away and the right portion of 60 the apparatus being shown in vertical central section.

Fig. 2 is a transverse sectional view on the line ABCD, Fig. 1.

Fig. 3 is a detail view drawn to a larger 65 scale showing the structure of the improved grain separating elements.

Fig. 4 is a partial front view of one of the segments formed with a large number of 70 alveoli of which the separating elements are made up.

Fig. 5 is an enlarged plan view of one of the alveoli, showing its configuration.

Figs. 6 and 7 are respectively partial sectional views on the lines EF and GH, Fig. 4. 75

Fig. 8 is a similar view to Fig. 1 showing a modification of the grain separator according to the invention, wherein the annular separating elements are arranged internally of their supporting cylinder. 80

Fig. 9 is a sectional view on the line IJ, Fig. 8.

Fig. 10 is an enlarged fragmentary sectional view showing two juxtaposed annular separating elements arranged internally of 85 their supporting cylinder.

Like reference characters designate like parts throughout the several views.

According to the embodiment of the invention illustrated in Figs. 1 to 7 inclusive, 90 the grain separator comprises a horizontal (or, if required, slightly slanting) shaft 1 rotatably mounted in suitable bearings 2 and 3 carried by a suitable framework which also serves for supporting the stationary 95 cylindrical drum-like outer casing 4. The shaft 1 is imparted a rotary motion by means of an outer fast pulley 5 and drives the cylinder 6 extending lengthwise in said casing and rigidly secured thereto in any convenient way. Upon the said cylinder are fixedly secured a plurality of separating elements constituted by frusto-conical or dish shaped ring members 7 arranged in juxtaposed relation to one another as shown for 100 forming, as it were, a zig-zag or saw-tooth outline or contour, so as to delineate between them grooves or flutings 7^a having the shape of isosceles triangles the apices of which are situated on the cylinder 6, 105 for a purpose to be hereinafter described. Each ring member 7 may be in one piece or 110

formed of a plurality of segments such as 8 (Fig. 2), such segments being slightly spaced at 9, if required.

The ring members 7 are secured to the outer face of the cylinder 6 in any approved way and preferably so as to be readily dismountable. They are formed along their inner edge, i. e., the one which is positioned adjacent the cylinder 6 with slits 10 the purpose of which will be explained hereinafter. Their outer free edges are united in pairs by any suitable means such as a flange or a rim whereby annular grain separating elements having, so to speak, bevelled edges are formed. Each annular bevel unit might be cast in one piece instead of being formed by the juxtaposition of two symmetrical frusto-conical rings or else formed of a number of V-shaped segments, as will be readily understood.

Each of the adjacent bevelled annular separating elements formed either of a V-shaped ring or of two juxtaposed frusto-conical rings united by their outer edges, as above described, is formed on the whole of its outer surface with a large number of alveoli or sockets 11, obtained either by cutting or during the casting process or by any other suitable means. These sockets or alveoli are of sufficient size to conveniently catch up and separate the proper grains (for instance wheat grains from oats grains) and are preferably shaped and arranged as shown in Figs. 4 and 5, their rectilinear side *ag* constituting their front or leading edge whereas their rounded or convex side *d* constitutes their rear edge connected to said leading edge by two rectilinear sides *cb* and *ef*. The arrows in Fig. 4 illustrate the direction of rotation of the separating elements.

The mass of commingled grains to be separated or sorted is introduced into the casing 4 through a feed inlet pipe 12 which opens in one extremity of this casing, the rotation of the shaft 1, cylinder 6 and separating elements 7 being adapted for conveying the grains towards the opposite extremity of said casing. The separating elements 7 dip into the mass of grains as it travels from the inlet extremity to the opposite extremity of the casing 4, whereby the alveoli or sockets 11 come in close contact with said grains and all grains susceptible of getting thereinto (for instance wheat grains) are promptly caught up, taken round by the rotation of the separating elements 7 and dropped off at 13 (Fig. 2) on the opposite side, as the said separating elements rotate. The grains thus dropping from the alveoli fall on a stationary or adjustable inclined board 14 and thence into one or more hoppers 15 which discharge them into any suitable receptacles. As to the grains that have not been caught up by

the alveoli owing to their size or shape (such as oats grains) they are gradually pushed longitudinally from any of the grooves 7^a into the following ones and through the spaces 9 between the adjacent ring elements 70 if the latter have a segmental structure by obliquely disposed blades 16 thrust into the slits 10 formed in the said ring elements 7. Such refuse grains finally reach the left extremity of the casing 4 (see Fig. 1) and are 75 discharged through a suitable chute (not shown) by the rotation of the screw 17 made fast on the end of the shaft 1.

As above explained, the formation of the separating or sorting alveoli on the contiguous faces of the ring members 7 has the great advantage of considerably increasing the number of the said alveoli for a determined volume of the apparatus, by comparison with grain separators wherein the alveoli are formed either directly in the outer face of a rotating cylinder such as 6 or, in such improved separators as above referred to, on discs or screw-blades fixed on a rotating longitudinal shaft such as 1. By the provision of juxtaposed frusto-conical ring members 7 forming annular elements delineating between them V-shaped grooves or flutings 7^a, the separating capacity of the apparatus is largely increased, the volume 95 of the said apparatus remaining substantially unchanged, whilst at the same time the provision of the said grooves 7^a ensures a thorough intermixing and stirring of the grains which together with the formation 100 of the alveoli 11 on obliquely disposed surfaces still further facilitates the getting of the proper grains thereinto and enhances the output of the apparatus.

According to the further embodiment of 105 the invention illustrated in Figs. 8 to 10, the ring members 7 are arranged internally of their supporting cylinder 6 instead of being arranged externally as in the first embodiment above described. The construction is simplified owing to the fact that the outer casing 4 may thus be dispensed with since the mass of commingled grains is fed into the cylinder 6 itself. In the construction represented in the drawing, said cylinder 6 is loosely mounted upon the shaft 1 and is driven by a belt 18 passing around its pulley-shaped outer end wall 6^a. Plates 19 and 20 are fixedly secured upon the shaft 1 for forming dust-tight seals.

The commingled grains are fed into the cylinder 6 by the inlet pipe 12 and are brought into the V-shaped grooves or flutings 7^a by inclined scoops 21 secured to the inner face of said cylinder. As in the first constructional embodiment, the grooves 7^a are delineated by juxtaposed frusto-conical rings 7 either in one piece or made up of a plurality of segmental portions 8 spaced apart if required. The ring members 7 are 130

formed on their outer faces with sockets or alveoli conveniently shaped and arranged as shown in Figs. 4 and 5 and adapted for catching up the proper grains (wheat grains for instance) and dropping them off at the opposite side where they are discharged. The refuse grains (oats grains for instance) which have not been caught up by the alveoli due to their size or shape are pushed from any of the grooves 7^a to the following ones by the obliquely disposed blades 16 thrust in the slits 10 formed in the ring members 7 and finally discharged at the end of the cylinder 6 through peripheral slots 22 (Fig. 8).

The discharging device for the grains that have been caught up by the sockets or alveoli 11 conveniently comprises a stationary arcuate trough 23 hung by clamping collars 24 from the shaft 1, transversely shaped as illustrated and having its upper edge formed as the teeth of a saw for engaging the gaps between the grooves 7^a so as to collect the grains escaping therefrom; said trough 23 is preferably slightly slanting lengthwise for facilitating the flow and discharge of the grains thus collected and its angular position in the cylinder 6 is preferably adjustable by means of an outer lever 25 made fast upon the shaft 1. The grains collected in the trough 23 as above explained are conveyed to the discharging chute 27 secured thereto, for example by a worm actuated by a suitable gearing or, alternately, as illustrated by a second arcuate trough 28 arranged internally of the trough 23, freely suspended from the shaft 1 and having a reciprocating motion imparted thereto by a cam 29 fixed upon the end spider 30 of the cylinder 6.

The traversing motion of the mass of commingled grains to be separated from one extremity of the apparatus to the other may be accelerated by means of inclined blades 31 fixed under the stationary trough 23 or by means of other blades also inclined but in a reverse direction and secured to the apices of the grooves 7^a.

In accordance with the patent statutes, the principles of construction and operation of the invention as well as two convenient constructional embodiments of same have been described. It will however be understood that same is not limited thereto and that numerous modifications might be introduced without departing from its scope and spirit as will now be emphasized in the subjoined claims.

What I claim and desire to secure by Letters Patent is:—

1. A grain separator comprising an outer casing, a rotary supporting cylinder mounted in said casing, a plurality of contiguous annular outwardly tapering separating elements arranged successively upon said cylinder

inder, each of said elements being formed by a pair of juxtaposed symmetrical frusto-conical ring members secured at their edges and formed on their outer surfaces with a large number of contiguous alveoli and means for feeding grain at one extremity of the casing to a degree to reach the lower portion of the separating elements. 70

2. A grain separator comprising a driven shaft, a rotary supporting cylinder mounted thereon, a plurality of annular outwardly tapering separating elements arranged in sequence on and contiguously fixed relative to said cylinder each of said elements being formed by a pair of juxtaposed symmetrical frusto-conical ring members formed on their outer surfaces with a large number of alveoli suitably sized and shaped for first picking up and afterwards dropping off proper grains from the mass of commingled grains and a stationary cylindrical casing enclosing the cylinder and separating elements, said casing being formed at one end with an inlet for said commingled grains and at the opposite end with an outlet for the selected 85 grains. 90

3. A grain separator comprising an outer elongated casing, a rotary supporting cylinder, and a sequence of contiguous annular outwardly tapering separating elements, each made up of juxtaposed ring members secured in pairs at their outer edges, each of the ring members comprising a number of segments radially spaced and formed adjacent the cylinder with slits, and angularly disposed blades having their ends passed into said slits for propelling the refuse grains from one end of the casing toward the other. 95 100

4. A grain separator comprising an outer elongated casing, a rotary supporting cylinder mounted thereon, a sequence of contiguous annular outwardly tapering separating elements made up of juxtaposed companion ring members secured in pair arrangement by their outer edges, each member comprising a plurality of frusto-conical segments radially spaced and formed on their outer surfaces with a large number of alveoli. 105 110

5. A grain separator comprising an outer elongated casing, a rotary supporting cylinder mounted thereon, a plurality of contiguous annular outwardly tapering separating elements arranged in pairs of ring members, and secured together at their outer edges, each ring member being formed on its outer surface with a large number of contiguous alveoli formed to present a rectilinear front edge and a convex rear edge, the size of the alveoli being determined by the size of the grain to be sorted. 115 120 125

6. A grain separator comprising a rotary cylinder a plurality of annular outwardly tapering separating elements each formed of a pair of juxtaposed ring members secured together at their outer edges, said ring mem- 130

bers being secured at similar edges to the cylinder and formed on their outer surfaces with a large number of contiguous alveoli having rectilinear leading edges and convex following edges, and means for supporting a mass of grain into which the separating elements may be moved in the operation of the cylinder.

7. A grain separator comprising a rotary supporting cylinder, a plurality of annular outwardly tapering separating elements secured by their outer edges to the inner face of said cylinder, juxtaposed and united by suitable means along their inner edges and formed on their outer surfaces with a large number of contiguous alveoli for catching up and afterwards dropping off and separating out the proper grains from a mass of commingled grains, an inlet pipe at one extremity of said cylinder, peripheral discharging slots for the refuse grains at the other extremity of said cylinder and a discharging device for the sorted grains constituted by a stationary arcuate trough preferably slightly slanting longitudinally and extending underneath the shaft on which said cylinder is mounted, the upper edge of said trough be-

ing saw-tooth shaped for engaging the grooves between the separating elements and collecting the grains dropping from their alveoli, and a conveyor in said trough for pushing the said grains towards the outlet.

8. A grain separator comprising a shaft, a rotary supporting cylinder mounted thereon, a plurality of annular outwardly tapering separating elements fixed by their outer juxtaposed edges to the inner face of said cylinder and formed on their outer surfaces with a large number of contiguous alveoli for sorting the proper grains from a mass of commingled grains fed at one extremity of said cylinder, a discharging trough located axially underneath said shaft for collecting the proper grains dropped from the alveoli and a second conveying trough arranged in the first named trough, freely suspended from said shaft and having a reciprocating motion imparted thereto by a cam rigidly mounted upon the said cylinder.

In testimony whereof I have signed my name to this specification.

CHARLES JEAN-BAPTISTE VIGUERIE.
